UNITED STATES PATENT OFFICE

134,366

DESIGN FOR A STAMPED TEXTILE FABRIC OR SIMILAR ARTICLE

Samuel Fixler, Chicago, Ill., assignor to Frederick
Herrschner Co., Chicago, Ill., a corporation of Illinois

Application October 5, 1942, Serial No. 108,434

Term of patent 7 years

To all whom it may concern:

Be it known that I, Samuel Fixler, a citizen of the United States and a resident of the city of Chicago, in the county of Cook, and State of Illinois, have invented a new, original, and ornamental Design for a Stamped Textile Fabric or Similar Article, of which the following is a specification, reference being had to the accompanying drawing, forming a part thereof.

On the drawing:

The figure represents a plan view of the stamped textile fabric or similar article, showing my new design.

I claim:

The ornamental design for a stamped textile fabric or similar article, as shown.

SAMUEL FIXLER.
